No. 12,836

MARCH 28, 1882

IRON DUKE.

UNITED STATES PATENT OFFICE.

GEORGE O. BERGSTROM, OF NEENAH, WISCONSIN, ASSIGNOR TO BERGSTROM BROTHERS & CO., OF SAME PLACE.

DESIGN FOR A STOVE.

SPECIFICATION forming part of Design No. 12,836, dated March 28, 1882.

Application filed October 15, 1881. Term of patent 14 years.

To all whom it may concern:

Be it known that I, GEORGE O. BERGSTROM, a citizen of the United States, residing at Neenah, in the county of Winnebago and State of Wisconsin, have invented and produced a new and original Design for Stoves, of which the following is a specification, reference being had to the accompanying drawings, forming part thereof.

- 10 The leading features of my design consist in the beads or fillets formed on the margin of the legs and the ornamental incised figures formed in their surfaces; in so forming the two oven-doors that they resemble in appearance a single door; in the deep continuous moldings formed immediately back from the edge of the oven-doors and the ornamental marginal and central figures formed thereon; in the broad continuous beveled edges and rounded corners of the top and bottom, which edges project beyond the sides and ends of the stove; in the Gothic windows and heavy panels, with the words "Iron Duke" formed in bas-relief upon the front doors beneath said windows; in the shape of the closet-door and the raised and incised figures formed thereon, and in the form of the side door over the hearth and the incised ornamental figures formed thereon.
  - 20
  - 25
  - 30
  - 35
  - 40
  - 45
  - 50
- A is the bead or fillet formed around the outer edges of the legs. B are the ornamental incised figures on the front surface of the legs. C and D are the oven doors, which are so formed that when closed they resemble a single door, they having a continuous surface throughout upon both sides of the line of contact.
- The deep molding E forms a continuous symmetrical curve from the upper end to the side of the doors, unbroken by the joint between said doors, and the bottom molding, F, is also formed in one continuous plane from the front to the rear of said doors. The border ornamental lines G extend continuously around the entire margin of said doors, apparently unbroken by the joint between them.
- a is a heavy ornamental panel formed in bas-relief upon the larger oven-door, upon the upper edge of which is an ornamental figure, I.
- The molding J and the panel K on the closet-door are substantially like those on the oven-door, while the incised figure L is similar in appearance to the figure I, and the incised

marginal lines and figures have the same general appearance on both doors. The moldings M of the end door to the fuel-box are also formed substantially like those of the oven and closet, all of which moldings are broad and deep, giving the doors a rich substantial appearance. Ornamental corner figures and marginal lines N are formed within the molding M.

The top and bottom of the stove have broad continuous beveled edges O and P and rounded corners Q. The edges O and P project past the sides and ends of the stove.

Gothic windows R are provided in each of the front doors, beneath which are heavy raised panels S, on which the words "Iron Duke" are formed in bas-relief.

I claim—

1. The design for stoves herein described, consisting in the beads or fillets A, forming the border or outline of the legs, and the ornamental incised figures B within said border. 75
2. The doors C and D, having smooth uniform surfaces and unbroken continuous moldings and incised marginal lines at and across their line of contact, whereby they more closely resemble in appearance a single door. 80
3. The broad deep moldings E, formed immediately back of the margin of the door, the ornamental incised marginal lines and figures G, central figures, I, and raised panel a, ornamented in bas-relief. 85
4. The Gothic windows R in the front doors and the raised panels S, formed beneath said windows on said doors, as shown. 90
5. The broad deep moldings M of the end door and the incised corner ornaments and lines N. 95
6. The design for stoves herein described, consisting in the configuration and arrangement of the ornaments in bas-relief, the moldings and incised figures on oven, closet-doors, and the front doors above the hearth, the Gothic windows in said front doors, the incised ornamental figures and moldings of the end door of the fire-box, the incised ornamental figures and borders of the legs, and the beveled edges and rounded corners of the projecting top and bottom, as described. 100

In testimony whereof I affix my signature in presence of two witnesses.

Witnesses: GEORGE O. BERGSTROM,
                    ALEX. MCNAUGHTON,
                    JOHN SHIELLS.
